UNITED STATES PATENT OFFICE

164,170

GAME BOARD

Howard M. Hay, Chicago, Ill.

Application December 26, 1950, Serial No. 13,590

Term of patent 14 years

(Cl. D34—5)

To all whom it may concern:

Be it known that I, Howard M. Hay, a citizen of the United States, residing at Chicago, State of Illinois, have invented a new, original, and ornamental Design for a Game Board, of which the following is a specification, reference being had to the accompanying drawing forming a part hereof.

The single figure is a perspective view of a game board, showing my new design.

I claim:

The ornamental design for a game board, as shown.

HOWARD M. HAY.
